UNITED STATES PATENT OFFICE

PHILIP P. CHAPIN AND WILLIAM J. KUPEC, OF NEW YORK, N. Y.

SIGN

Application filed August 4, 1928. Serial No. 297,423.

This invention relates to signs, and particularly to the type wherein a darkened mirror receives a skylighted designation and reflects it to the observer.

5 The principal object of the invention is to provide a simple, inexpensive, efficient, and improved sign of the above type, wherewith the same designation may be reflected to the observer in luminous form in darkness, with-
10 out use of artificial light or electric current, as well as in skylighted form during day-
light.

Other objects and advantages will herein-
after appear.

15 In the accompanying drawings,—

Fig. 1 shows a perspective view of the sign.

Fig. 2 is a transverse-sectional side eleva-
tion of the sign shown in Fig. 1.

20 Fig. 3 shows a perspective view of a modi-
fication of the invention.

Fig. 4 is a longitudinal cross-sectional eleva-
tion of the sign member shown in Fig. 3.

The sign 1 comprises a casing 2 having a
25 roof-wall 3, an oblique wall 4, and upright
end-walls 5, to which are preferably secured
brackets 6 for fastening the sign in any de-
sired location. Said roof-wall consists of a
30 frame 7 which is secured to the end-walls 5
at 8 and carries a plate 9, preferably of glass,
on which is painted or otherwise inscribed
the desired designation 10. The oblique
wall 5 consists of a frame 11 which carries a
35 mirror 12, whereby the said several walls
comprising the casing form a darkened cham-
ber 13, the front side of which is open and
presents the mirror 12 to view. In making
the designation 10 upon the sign member 8
40 we utilize such paints or substances as will
be translucent to daylight, and in darkness
will be self-luminous or glowing, resort be-
ing had to radio-active materials or com-
pounds having a meso-thorium base, phos-
45 phorescent materials or compounds, or any
other similarly acting substances, and in
making the designations 10 we either pro-
duce the characters themselves in the trans-
lucent self-luminous paint and make the
50 background opaque, or vice versa; or we
make the letters in colored translucent paint
with the background opaque, or vice versa,

and in either of the latter cases make the
outline of the letters in the translucent self-
luminous paint.

In the operation of this sign the sunlight
or skylight strikes the roof-wall 3 and pass-
ing through the translucent designation 10
reflects the latter in the mirror-wall 12, which
in turn reflects the designation outwardly
horizontally toward the observer. During
nighttime or in any darkened situation the
self-luminous designation 10 reflects its glow
into the mirror 12, which in turn reflects the
designation outwardly toward the observer,
who thus sees it in the form of upright bright-
ly illuminated characters.

According to the modification shown in
Figs. 3, 4, the characters 15 composing the
designation 10 are made out of glass tubing
16 which is filled with any suitable substance
17, preferably in liquid form, that possesses
the quality of being self-luminous or glow-
ing in darkness, and at the same time is trans-
lucent to daylight. The characters 15 are
set in in mountings or openings 18 formed in
10 an opaque plate 19, which may be of metal,
and when the daylight strikes this plate, or
when this sign is brought in a darkened sit-
uation, it produces the same results as those
above described in connection with the sign
20 illustrated in Figs. 1, 2.

Variations may be resorted to within the
scope of the invention, and portions of the
improvements may be used without others.

Having thus described our invention, we
claim:—

1. The combination of a member disposed
as a skylight, said member having thereon
designations made up of translucent self-lu-
minous material, and a mirror reflecting the
translucent quality of said designations to
the observer during daylight and reflecting
the luminous quality of said designations to
the observer during darkness.

2. The combination of a member disposed
as a skylight, said member having thereon
designations composed of tubular glass, said
glass being filled with translucent self-lu-
minous material, and a mirror reflecting the
translucent quality of said designations to
the observer during daylight and reflecting
the luminous quality of said designations to
the observer during darkness.

the luminous quality of said designations to the observer during darkness.

Signed at the city of New York, in the county of New York and State of New York,
5 this 3rd day of August A. D. 1928.

PHILIP P. CHAPIN.
WILLIAM J. KUPEC.
